MUFFLER DEVICE

Patrick J. Conlin, 1770 Davie St., Vancouver,
British Columbia, Canada
Filed Dec. 4, 1961, Ser. No. 156,584
3 Claims. (Cl. 181—58)

This invention relates to mufflers for the exhaust of internal combustion engines and more particularly to an improved design characterized by the utilization of the individual pulsations of the exhaust gases as the means for effecting the silencing or muffling of the exhaust.

The principal object of the invention is to provide a muffler for internal combustion engine exhaust in which each individual pulsation is divided into two parts and the two parts caused to oppose one another with resultant "canceling out" of each other and consequent substantial elimination of noise.

Another object of the invention is to provide a muffler for the exhaust gases of an internal combustion engine characterized by small size, simple construction, and having passages for the exhaust gases so arranged as to cause a minimum of back pressure on the engine exhaust system.

With the foregoing objects in view, together with such additional objects and advantages as may subsequently appear, the invention resides in the parts, and in the construction, combination and arrangement of parts described, by way of example, in the following specification of a presently preferred embodiment of the invention, reference being had to the accompanying drawings which form a part of said specification and in which drawings:

FIG. 1 is a side elevational view of the muffler embodying the invention as viewed in the direction of the entrance of gases into the inlet port or pipe of the muffler.

FIG. 2 is an end elevational view as viewed from the right hand or exhaust end of a muffler, having reference to FIG. 1,

FIG. 3 is a top plan view of the muffler shown in FIG. 1 and having reference to the position of the muffler shown in FIG. 1,

FIG. 4 is a medial sectional view taken on the line 4—4 of FIG. 2,

FIGS. 5 and 6 are, respectively, medial sectional and transverse sectional views taken on the lines 5—5 and 6—6 of FIG. 1, and

FIG. 7 is a perspective, fragmentary view of the end of the exhaust or discharge pipe of the muffler which is concealed within the muffler body.

Referring to the drawings, the illustrated embodiment of the invention comprises a body 1 having a cylindrical portion 2 preferably of greater diameter than length and having a flat end plate 3 closing one end thereof and a frusto-conical end portion 4 of approximately the same axial length as the cylindrical portion 2 closing the other end thereof. Any desired and convenient form of manufacture of the body may be employed. The cylindrical portion 2, end plate 3 and frusto-conical portion 4 may first be formed separately and welded together or the cylindrical portion 2 may be formed integrally with either of the other portions and then united to the remaining portion by a single line of welding as may be most expedient. Still further, one-half of the cylindrical portion

2

2 may be formed integrally with the frusto-conical portion 4 and the other half with the end plate 3 with the meeting edges thereof each cut away to form an entrance for the inlet pipe 5.

5 The inlet pipe 5 projects from the muffler body and is attachable to the pipe carrying the engine exhaust and the pipe 5 enters and is welded to the side of the cylindrical portion 2 with the side of said pipe removed from the axial center line of the muffler body disposed substantially tangentially thereto. An exhaust pipe 6 extends in the said axial line through the end plate 3 to which it is welded and has the inner and thereof cut away at opposite sides as at 7, 7 to form oppositely disposed side openings separated by oppositely disposed tongues 8, 8 which are welded to the inner face of the end portion 5 at the smaller end thereof.

The exhaust gases entering the muffler body through the tangentially disposed inlet pipe 5 are caused to move circularly about the interior of the body and at increasing rotational speeds as they travel along the decreasing diameter of the frusto-conical end portion 4. This increasing speed of rotation serves in part to cause the successive pulsations of the exhaust to damp or "cancel" each other out since they are not in synchronism. Finally, 20 each such pulsation must enter the exhaust pipe 6 at the opposed openings therein and the result is that since they are equal both in timing and in the force exerted, they cancel each other out resulting in a substantially noiseless exhaust. It is to be particularly noted that the muffler 25 contains no baffle means or other obstruction to the free flow of the exhaust gases through the device. Therefore, assuming a muffler having pipes at least equal in size to the pipe leading from the engine exhaust to which the muffler is attached, the back pressure produced by 30 the muffler, per se, is reduced to a minimum.

While in the foregoing specification, there has been disclosed a presently preferred embodiment of the invention, the invention is not to be deemed to be limited to the precise details of construction thus disclosed by 35 way of example, and it will be understood that the invention includes as well all such changes and modifications in the parts, and in the construction, combination and arrangement of parts as shall come within the purview of the appended claims.

I claim:

1. A muffler device for the exhaust of an internal combustion engine comprising

a hollow, cylindrical body having a circular side wall, a first end wall comprising a flat plate at one end of said side wall, and a frusto-conical portion closing the opposite end of said side wall,

an inlet pipe extending through said side wall disposed substantially tangentially thereto operative to conduct received exhaust gases into said body,

and an exhaust pipe extending through said first named end wall in the axial line of said body operative to conduct exhaust gases from said body;

said exhaust pipe within said body being attached to the inner face of said frusto-conical portion and having

a pair of laterally opposite side openings adjacent to said frusto-conical portion through which the exhaust gases enter said exhaust pipe.

2. A muffler device as claimed in claim 1 in which said side wall through which said exhaust pipe extends is

disposed in a plane normal to the axial line of said cylindrical body.

3. A muffler device as claimed in claim 1 in which said opposite openings in said exhaust pipe are disposed in close proximity to the inner face of said frusto-conical end of said body,

and in which the end of said exhaust pipe within said body is fixed to said inner face at the apical portion thereof.
